ABSTRACT

(*) Notice: Subject to any disclaimer, the term of this patent is extended or adjusted under 35 U.S.C. 154(b) by 0 days.

An electrical system includes a first substrate having a first contact portion thereon and a second substrate having a second contact portion thereon. An electrical connector is arranged between the first and second substrates for establishing electrical connection therebetween. The electrical connector includes a plurality of wafer stacked together and each wafer includes at least a passageway defined therein having ends facing the first and second substrates. Each passageway has a terminal moveably supported therein and has end contacting portions electrically contacting with first and second contact portions of said first and second substrates. The terminal includes an arm abutting against an inner side of the passageway.

FIELD OF THE INVENTION

The present invention relates to an electrical connector, and more particularly to an electrical connector configured by wafers including moveable contacts thereby featuring simple, reliable connections.

DESCRIPTION OF THE PRIOR ART

Making an electrical connector by means of wafers has been known to the industry. However, all contacts are fixedly and securely attached to a wafer, typically as disclosed as below.

U.S. Pat. No. 5,993,259 issued to Stokoe et al discloses an electrical connector of such application. The connector disclosed in the '259 patent includes a plurality of modularized wafers bounded together. As shown in FIG. 4 of the '259 patent, the terminals are stamped from a metal sheet, then embedded within an insulative material to form the wafer.

U.S. Pat No. 6,083,047 issued to Paagman discloses an approach to make a high-density connector by introducing the use of printed circuit board. According to teaching of the '047 patent, conductive traces are formed on surfaces of the printed circuit board in a mirror-image arrangement, typically shown in FIG. 12.

As known to the skilled in the art, electrical connection between two terminals is generally facilitated by normal force exerted from one terminal to the other. However, since surface of the terminal could be contaminated by dust or oxidation, it is preferable to generate a wiping displacement between two terminals during mating. With the wiping displacement between the terminals, dust or oxidation on the terminal could be wiped out, thereby ensuring reliable electrical connection between two mated terminals.

The suggestions disclosed above have solder tails soldered to the printed circuit board, while connecting portions make connection through wiping.

In addition, since the terminals are fixedly embedded to the wafer, normal force provided by the terminals is then fixed.

Another problem of the prior art is that during the engagement of the terminals and the printed circuit board, there is a possibility of collapse of the terminals because an end of the terminal is soldered to the printed circuit board, especially to the terminals with tiny configuration and dimension. In addition, conventional arrangement of the terminal is always parallel to direction of the inserted printed circuit board.

Co-pending U.S. patent application entitled to "Electrical Connector", commonly assigned to the same assignee and filed on May 15, 2001, Ser. No. 09/858,841, discloses an electrical connector having terminals moveably mounted on terminal supports. The specification is attached as for reference.

SUMMARY OF THE INVENTION

It is an objective of this invention to provide an electrical connector configured by a plurality of wafers. The number of wafers can be increased accordingly to meet different applications.

Another objective of this invention is to provide a wafer in which terminals are dynamically received within passage-

ways thereof thereby properly avoiding collapse of the terminals by movement of the terminal within the passage-way.

In order to achieve to the objectives set forth, an electrical system in accordance with the present invention includes a first substrate having a first contact portion thereon and a second substrate having a second contact portion thereon. An electrical connector is arranged between the first and second substrates for establishing electrical connection therewith. The electrical connector includes a plurality of wafer stacked together and each wafer includes at least a passageway defined therein having ends facing the first and second substrates. Each passageway has a terminal moveably supported therein and has end contacting portions electrically contacting with the first and second contact portions of said first and second substrates. The terminal includes an arm abutting against an inner side of the passageway.

SUMMARY OF THE DRAWINGS

Other objectives and further features of the present invention will be apparent from the following detailed description when read in conjunction with the accompanying drawings, in which:

FIG. 1 is a front view of a wafer in accordance with the present invention before a daughter is inserted;

FIG. 2 is similar to FIG. 1 with the daughter card inserted;

FIG. 3 is a perspective view of a connector configured by sixteen wafers of FIG. 1;

FIG. 4 is a bottom view of FIG. 3;

FIGS. 5A to 5C are illustrations showing the daughter card is electrically connected to the motherboard via the connector in accordance with the present invention;

FIG. 6 is a bottom view of a wafer in accordance with a second embodiment of the present invention; and

FIG. 7 is a front view of FIG. 6.

**DETAILED DESCRIPTION OF PREFERRED
EMBODIMENTS**

Referring to FIGS. 1 and 2, a wafer 10 in accordance with the present invention comprises a base portion 11, of a desired thickness, having a card receiving passageway 12 extending from a top surface 11a thereof. The base portion 11 further defines first and second passageways 13, and 14, symmetrically arranged with respect to the card receiving passageway 12 and in to a bottom surface 11b of the base portion 11. The base portion 11 further defines a recess 19 extending upward from the bottom surface 11b and merging with end portions 13a, 14a of the passageways 13, 14.

First and second terminals 21, 22 are received in the passageways 13, 14, respectively. The terminal 21 (22) includes a base portion 21a (22a), first and second contact portions 21b, 21c (22b, 22c). Each terminal 21 (22) further includes an arm 21d (22d) extending from the base portion 21a (22a), respectively. The length of the terminal 21 (22) is arranged longer than the length of the passageway 13 (14).

As it can be readily seen from FIG. 1, the first contact portion 21b (2b) of the terminal 21 (22) extends into the recess 19 and flush to the bottom surface 11b, while the second contact portion 21c (22c) extends into the card receiving passageway 12.

In practice, the bottom surface 11b is rested on a mother board 31 (FIGS. 5A to 5C) on which conductive pads 32, 33 are provided. When the wafer 10 is securely mounted onto

the motherboard 31, the first contact portions 21b, 22b are in contact with the conductive pads 32, 33 respectively, while the second contact portion 21c, 22c extend into the card receiving passageway 12.

When a daughter card 35 having conductive pads 36, 37 thereon is inserted into the card receiving passageway 12 and in contact with the second contact portions 21c, 22c, the terminals 21, 22 are forced to move along the passageways 13, 14, respectively, such that the first contact portions 21b, 22b wipe over the conductive pads 32, 33. In addition, since the second contact portions 21c, 22c are driven into the passageways 13, 14, the second contact portions 21c, 22c wipe over the conductive pads 36, 37, respectively. Accordingly, reliably electrical connections between the contact portions 21b, 22b, 21c, and 22c and the conductive pads 32, 33, 36, and 37 are achieved.

In addition to the wiping motion occurring between the first and second contact portions 21b, 22b, 21c, and 22c and the conductive pads 32, 33, 36 and 37, dynamic motion of the terminals 21, 22 within the passageways 13, 14 can also effectively reduce the possibility of the collapse of the terminals 21, 22 during the engagement with the daughter card 35. As shown in FIG. 1, prior to the engagement, the base portion 21a, 22a of the terminals 21, 22 are straight. During the engagement, the base portion 21a deforms such that the first contact portions 21b, 22b wipes over the conductive pads 32, 33 thereby preventing terminals 21, 22 from stubbing and yielding, as shown in FIG. 2. Without this dynamic motion and subsequent wiping action of the first contact portions 21b, 22b with respect to the conductive pads 32, 33, it is possible that the terminals 21, 22 may stub, yield and collapse. In addition, the provision of the arms 21d, 22d will also force the base portion 21a, 22a back to its original position once the daughter card 35 is withdrawn from the card receiving passageway 12. This results in excellent mechanical performance even though the size of the terminals 21, 22 can be quite small.

In addition, since the passageways 13, 14 are in slant arrangement and the terminals 21, 22 are obliquely supported in the passageways 13, 14, the first contact portions 21b, 22b contact the conductive pads 32, 33 angularly. Accordingly, the wiping motion of the first contact portions 21b, 22b with respect to the conductive pads 32, 33 occurs without causing excess stress to the terminals 21, 22 thereby properly avoiding permanent deformation of the terminals 21, 22.

Furthermore, the provision of the recess 19 release the extension of the first contact portions 21b, 22b of the terminals 21, 22. As the second contact portions 21c, 22c of the terminals 21, 22 displace normal to the daughter card they retreat into the passageways 13, 14 while engaging with the daughter card 35. This forces the first contact portions 21b, 22b to extend into the recess 19. Without the provision of the recess 19, the wiping motion is limited to a short distance, while with the provision of the wiping movement, the wiping movement of the contact portions 21b, 22b can be properly extended. However, the recess 19 can also be replaced by an enlarged portion of each passageways 13, 14.

In the above described embodiment, the passageways 13, 14 are arranged in the same plane, while in a second embodiment, the passageways 113, 114 can be arranged oppositely on first and second surfaces 110a, 110b of a wafer 110 according to a second embodiment of the present invention. Each passageway 113 (114) is provided with an enlarged portion 113a (114a) for extension of contact portions 121b (122b) of the terminals 121 (122), as clearly

shown in FIGS. 6 and 7. The terminals 21, 22 assembled therein are same as the first embodiment. The wafer 110 also defines a card receiving passageway 112 for receiving a daughter card therein.

FIGS. 3 and 4 are views showing a connector 1 configured by sixteen wafers 10 disclosed above. As it can be readily seen, the wafer 10 is defined with holes 16. When the wafers 10 are assembled, a fastening device (not shown) can extend through to each hole to securely attach the wafers 10 together. Similarly, many external geometric shapes attached to each wafer would provide alternative methods of attaching the wafers 10 together.

FIGS. 5A to 5C detailedly illustrate how the daughter card 35 is electrically connected to a motherboard 31 by the connector 1 disclosed above.

It can be understood that the invention may be embodied in other specific forms without departing from the spirit or central characteristics thereof. The present examples and embodiments, therefore, are to be considered in all respects as illustrative and not restrictive, and the invention is not to be limited to the details given herein.

We claim:

1. An electrical system, comprising:

a first substrate having a first conductive pad thereon; a second substrate having a second conductive pad thereon; and

an electrical connector having first and second surfaces corresponding said first and second substrates for establishing electrical connections therebetween, the electrical connector including a housing configured by wafers stacked together each having a passageway extending from said first surface to said second surface; a card receiving passageway for receiving said second substrate therein; said second surface defining an inner wall of said card receiving passageway and

a terminal moveably received in said passageway having contacting portions adapted to cause a wiping motion along first and second conductive pads of said first and second substrate;

wherein said passageway includes an enlarged portion in which said first contact portion of said terminal extends into during said wiping movement along said first conductive pads of said first substrate.

2. An electrical system, comprising:

a first substrate having a first conductive pad thereon; a second substrate having a second conductive pad thereon, said second substrate being arranged orthogonal with respect to said first substrate; and

an electrical connector arranged between the first and second substrates for establishing electrical connections therebetween and defining first and second surfaces with said second surface facing said first substrate, the electrical connector including a plurality of wafers stacked together, each wafer including a card receiving passageway for receiving said second substrate therein and a plurality of passageways symmetrically arranged with respect to said card receiving passageway and extending from inner walls of said card receiving passageway to said second surface of said connector; and

a plurality of terminals each moveably received in corresponding said passageways and having first and second contact portions;

wherein before said second substrate is inserted into said card receiving passageway, said first contact portion

rests on first conductive pad of said first substrate, while said second contact portion extends into said card receiving passageway;

wherein when said second substrate is inserted into said card receiving passageway and in contact with said second contact portion of said terminal, said terminal is driven to move along said passageway such that both said first and second contact portions wipes, respectively, over first and second conductive pads of said first and second substrates thereby providing effective and reliable electrical connections therebetween. 10

3. An electrical system, comprising:

a first substrate having a first conductive pad thereon; a second substrate having a second conductive pad thereon, said second substrate being arranged orthogonal with respect to said first substrate; and 15

an electrical connector arranged between the first and second substrates for establishing electrical connections therebetween and defining first and second surfaces with said second surface facing said first substrate, the electrical connector including a plurality of wafers stacked together, each wafer including a card 20

receiving passageway for receiving said second substrate therein and a plurality of passageways symmetrically arranged with respect to said card receiving passageway and extending from inner walls of said card receiving passageway to said second surface of said connector; and

a plurality of terminals each moveably received in corresponding said passageways and having first and second contact portions;

wherein before said second substrate is inserted into said card receiving passageway, said first contact portion rests on first conductive pad of said first substrate, while said second contact portion extends into said card receiving passageway; 10

wherein when said second substrate is inserted into said card receiving passageway and in contact with said second contact portion of said terminal, said second contact portion is driven into said passageway, while the first contact portion extends outward from said passageway.
